UNITED STATES PATENT OFFICE.

WILLIAM WRIGHT, OF CHICAGO, ILLINOIS.

YOKE FOR CAR-COUPLED DRAW-BARS.

1,125,430.

Specification of Letters Patent. Patented Jan. 19, 1915.

Application filed July 23, 1912. Serial No. 711,714.

To all whom it may concern:

Be it known that I, WILLIAM WRIGHT, a citizen of the United States, residing at Chicago, Illinois, have invented a certain new and useful Improvement in Yokes for Car-Coupler Draw-Bars, of which the following is a full, clear, and exact description, such as will enable others skilled in the art to which it appertains to make and use the same, reference being had to the accompanying drawings, forming part of this specification, in which—

Figure 1 is a side elevation of a drawbar yoke of my improved construction. Fig. 2 is a plan view of the yoke. Fig. 3 is a front elevation of the yoke with the draw bar shown in section.

My invention relates to new and useful improvements in yokes such as are utilized as connections between the drawbars of car couplers and parts of the draft rigging, the principal object of my invention being to construct a simple, strong, rigid one-piece yoke having its forward end shaped so as to embrace the head on the rear end of the coupler drawbar.

Further objects of my invention are to construct a drawbar yoke that will meet the recommended practice of the M. C. B., and the forward ends of the two parts of the yoke being provided with side plates or extensions embracing the sides of the head on the rear end of the drawbar, and provided with means for engaging the drawbar so as to materially reduce the shearing strains imparted to the fastening devices during service, which arrangement holds the rear end of the drawbar in proper position and prevents rearward longitudinal movement thereof with respect to the yoke, even though the fastening devices be sheared or broken.

To the above purposes my invention consists in certain novel features of construction and arrangement of parts hereinafter more fully described and claimed.

Referring by numerals to the accompanying drawings, 1 designates the coupler drawbar provided on its rear end with the usual head 2, and there being shoulders 3 formed between the front side of said head and the body of said drawbar. The yoke, as shown, is formed in a single piece, preferably by casting, and comprises a pair of horizontally disposed parallel legs 4 that are united at their rear ends by a vertically

disposed plate 5, which, in service, bears directly against one of the follower blocks of the draft rigging. The forward ends of the legs 4 lie directly against the top and bottom faces of the head 2 and the extreme forward ends of said legs are turned inwardly, as designated by 6, and these portions engage the shoulders 3 on the front side of said head.

Formed integral with the forward end portions of the legs 4 are side plates or extensions 7 which occupy positions at the sides of the head 2, said plates or extensions meeting at the medial line of said head. Formed in the front edges of these plates at the points where the same meet are notches 8 around which are formed reinforcing ribs 9 that are integral with the plates 7. These notches form a rectangular seat for the rear portion of a horizontally disposed key 10 that passes through the rear portion of the drawbar immediately in front of the head 2 thereof. Bolts or rivets 11 pass through the forward ends of the legs 4 and through the head 2, thereby securely fastening said parts together.

When my improved yoke is attached to the draw bar, the shoulders 3 bear directly against the inwardly bent ends 6 of the yoke, thereby providing engagement of the draw bar and yoke which will relieve the bolts or rivets 11 of shearing stresses during pull on the draw bar. The cross key 10, bearing against the shoulders or seats formed in the plates 7, will prevent rearward movement of the draw bar relative to the yoke and relieve the bolts or rivets 11 of any shearing stresses occasioned by the yoke bringing up against a transverse member or other obstruction upon an abnormal thrust of the draw bar, or breakage of a draft spring or draft lugs. I do not claim as my invention the construction of yoke whereby side flanges are adapted to take up side strains between the yoke and the coupler.

The reinforcing ribs 9 around the notches 8 provide extra wide bearings for the projecting ends of the key 10.

A drawbar yoke of my improved construction can be easily and cheaply manufactured for the reason that it is formed in a single piece, is constructed so as to meet the requirements of standard practice, and the side plates or extensions on the forward ends of the legs of the yoke provide means whereby a strong, substantial and rigid

joint is formed between said yoke and draw bar.

It will be readily understood that minor changes in the size, form and construction 5 of the various parts of my improved draw bar yoke can be made and substituted for those herein shown and described without departing from the spirit of my invention, the scope of which is set forth in the appended claims.

I claim:

1. In a draft gear in combination, a draw bar having a head on its rear end, a yoke formed in a single piece and comprising a 15 vertically disposed rear plate, a pair of parallel legs integral with the top and bottom of said plate, pairs of laterally disposed notched plates integral with the forward end of each leg, said pairs of plates, together with 20 the forward ends of the legs being disposed to embrace the head on the rear end of the draw bar, rivets seated in the forward ends of the legs and the head of the draw bar for connecting the yoke to the draw bar, a key 25 passing transversely through the rear por-

tion of the draw bar, the ends of which key engage in the notches formed in the said pairs of plates.

2. The combination with a draw bar having a head on its rear end, of a draw bar 30 yoke formed in a single piece and comprising a pair of parallel legs, a vertically disposed plate connecting the legs at one end, a pair of laterally disposed plates integral with each leg at its other end, which pairs of 35 plates are provided with key seats, lugs integral with said plates adjacent to said key seats, a key seated in the draw bar and having portions disposed in the key seats and bearing against the lugs adjacent thereto, and 40 fastening means seated in the forward portions of the legs and the rear portions of the draw bar.

In testimony whereof I hereunto affix my signature in the presence of two witnesses, 50 this 17th day of July, 1912.

WILLIAM WRIGHT.
